UNITED STATES PATENT OFFICE.

E. PARMLY BROWN, OF FLUSHING, NEW YORK, ASSIGNOR TO HENRY CRAIK HOWELLS, OF SAME PLACE.

IMPROVEMENT IN DENTAL RUBBER DAMS.

Specification forming part of Letters Patent No. **174,942**, dated March 21, 1876; application filed January 25, 1876.

To all whom it may concern:

Be it known that I, E. PARMLY BROWN, of Flushing, State of New York, have invented an Improved Dental Rubber Dam, of which the following is a specification:

The object of my invention is to produce a rubber dam for the use of dentists, which shall more nearly fit the mouth, and lie smoothly and more naturally therein without the puckering and wrinkling, and constant tendency to pull off from the tooth to which the present form of rubber dam is liable. To this end I mold the rubber in pieces of the proper size for use, with a concave depression of an oval or other convenient shape, to suit the locations of the different teeth.

In the accompanying full-sized drawing, Figure 1 is a horizontal projection of the dam, showing the location and one of the forms of the depression; and Figs. 2 and 3 are sections at A B and C D, respectively.

I claim as my invention and desire to secure by Letters Patent—

In a dental rubber dam, a concave or depression, of whatever shape, molded therein for the purpose of fitting naturally in the mouth without stretching and puckering, all as arranged and described.

E. PARMLY BROWN.
